SINK

Ralph H. Culley, Rochester, N. Y.

Application April 15, 1947, Serial No. 138,419

Term of patent 14 years

(Cl. D4—2)

To all whom it may concern:

Be it known that I, Ralph H. Culley, a citizen of the United States, residing at Rochester, in the county of Monroe and State of New York, have invented a new, original, and ornamental Design for a Sink, of which the following is a specification, reference being had to the accompanying drawing, forming a part hereof.

Fig. 1 is a top plan view of a sink showing my new design;

Fig. 2 is a front elevational view;

Fig. 3 is a perspective view;

Fig. 4 is a sectional view taken on line IV—IV of Fig. 1; and

Fig. 5 is a sectional view taken on line V—V of Fig. 1.

I claim:

The ornamental design for a sink, as shown.
RALPH H. CULLEY.
